UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR SHAPING UPPERS OVER LASTS

Application filed April 8, 1931. Serial No. 528,611.

This invention relates to machines for use in the manufacture of shoes for shaping uppers over lasts, and is herein illustrated as applied to a pulling-over machine of a well-known type many of the characteristic features of which are disclosed in Letters Patent No. 1,029,387, granted on June 11, 1912, upon an application of R. F. McFeely, although it is to be understood that the invention is not thus limited in its applicability.

Pulling-over machines of the above-mentioned type include in their organization upper-fastening mechanisms which are movable laterally of the shoe at the opposite sides 15 of the forepart into upper-fastening positions and are constructed to drive at each side a plurality of fastenings spaced apart lengthwise of the shoe near the edge of the shoe bottom. In order to position the different 20 fastenings at the proper distances from the edge of the shoe bottom, whatever may be the shape and the position of the shoe, each side fastening mechanism is so mounted as to permit it to be turned about an axis extending 25 heightwise of the shoe, and as the mechanism is moved toward upper-fastening position it is adjusted about its axis under control of the shoe. In machines as commonly constructed heretofore such adjustment is 30 effected indirectly by the shoe through the action on the fastening mechanism of shoe-clamping means including a rubber pad previously applied in yielding engagement with the upper at the side of the shoe.

An object of the present invention is to afford increased insurance that fastenings such, for example, as those above referred to, will be located in proper relation to the shoe, and to this and other ends the invention provides novel means for determining the position of upper-fastening mechanism in its relation to the shoe prior to the driving of the fastenings. For the purposes in view, in the construction herein shown, each of the upper- 45 fastening mechanisms at the opposite sides of the shoe carries members which are arranged to engage the side of the shoe in different locations spaced apart lengthwise of the shoe to adjust the mechanism about its axis in accordance with the shape and position of

the shoe, so that the shoe is directly effective to determine accurately the position of the mechanism. These members, as illustrated, are so constructed and arranged as to engage the shoe positively, although in some of its 55 novel and useful aspects the invention is not limited to positive control of the upper-fastening mechanism. Preferably, the shoe-engaging members are spaced widely apart, to facilitate quick and accurate adjustment of 60 the fastening mechanism under control of the shoe, the construction shown being such that the members engage the shoe respectively at the front and at the rear of the group of fastenings and also at the front and at the 65 rear of the shoe-clamping means. In accordance with another feature, also, the shoe-engaging members are adjustable to vary the relation of the fastenings to the edge of the 70 shoe bottom.

The novel features of the invention will now be more particularly described by reference to the accompanying drawings and pointed out in the claims.

In the drawings,

Fig. 1 is a view from the front of a machine in which the invention is embodied, showing portions of the upper-pulling, clamping and fastening mechanisms that operate at one side of the shoe, portions of the structure being broken away;

Fig. 2 is a view showing parts in section on the line II—II of Fig. 1 and showing, in addition, portions of the operating instrumentalities at the other side of the shoe and 85 at the end of the toe;

Fig. 3 is a section on the line III—III of Fig. 2;

Fig. 4 is a section on the line IV—IV of Fig. 2; and

Fig. 5 is a perspective view of a portion of the means whereby the fastening mechanism is mounted for turning movement.

In view of the disclosure, in the above-mentioned and other prior Letters Patent, of characteristics of the general organization of machines of the well-known type illustrated, only such parts as it is necessary to refer to for an understanding of this invention are herein shown and will be particular- 95 105

ly described. It will be understood that such a machine is provided with grippers for pulling the upper over the last at the end of the toe and at the opposite sides of the forepart, 5 the toe gripper jaws being shown in section at 10 (Fig. 2) and the front and rear pairs of side gripper jaws at 12 and 14, respectively. The shoe is supported against the pull of the grippers by a sole rest 16. After the pulling 10 of the upper the shoe is engaged at each side of the forepart by a pair of clamp members 18 and 20, the member 18 consisting of a rubber pad which clamps the upper against the side of the last near the edge of the shoe 15 bottom and the member 20 consisting of a metal plate which engages the shoe somewhat underneath the forepart to support it against pressure subsequently applied on its bottom face in laying the margin of the upper inwardly over the insole and fastening it. The 20 clamp members at each side are carried by an arm 22 that is swung inwardly toward the shoe, the members being mounted respectively on slides 24 and 26 provided with rack 25 teeth engaged by a pinion 28, so that the two members adjust themselves to the shoe.

After the shoe has been clamped and supported as above described, the margin of the upper is wiped inwardly over the insole at 30 the end of the toe and the sides of the forepart and fastenings, customarily tacks, are driven to fasten it in pulled-over position, the grippers releasing the upper to permit these operations. The means for thus operating upon the upper at the end of the toe need not be described in detail. For operating at the sides of the forepart there are provided opposite side arms 30, a portion of one of 35 which is shown in Fig. 1, these arms being mounted to swing laterally of the shoe and being swung inwardly toward the shoe at the proper time in the cycle of the machine, as fully described in the above-mentioned Letters Patent. Each arm 30 carries at its 40 lower end a pair of wipers 32 and 34 for wiping the margin of the upper inwardly over the insole, and means for driving a plurality of tacks, herein shown as three in number, in different locations spaced apart along 45 the side of the shoe bottom to fasten the upper in pulled-over position. The tack-driving means comprises drivers 36 arranged to cooperate with tack holders 38 and 40 secured to a block or holder 42 which also supports 50 the wipers 32 and 34. The wipers are controlled by means which need not be described in detail, since the construction is substantially as disclosed in Letters Patent No. 1,381, 55 162, granted on June 14, 1921, upon an application of U. J. Bouchard.

In common also with machines heretofore in use, the construction shown is such that the upper-fastening mechanism on each of the side arms 30, together with the wipers 32 and 60 34, may be turned about an axis extending

heightwise of the shoe to position the tacks in proper relation to the edge of the shoe bottom. For this purpose the block 42 with its wipers and tack holders is secured to the lower end of a member 44 (Figs. 1 and 5) 70 which is mounted in a recess in one side of the arm 30, the securing means comprising a bolt 46 extending through lugs 48 on the lower end of the member 44 and arranged to cooperate with a hook-shaped projection 50 which is formed on a plate integral with the tack holder 40 and partially embraces the bolt between the lugs. There is also a tongue and groove connection 52 (Fig. 1) between the member 44 and the tack holder 40, which assists in maintaining the parts in proper relation to one another. By a nut 54 on the bolt 46 the hook-shaped projection 50 is clamped between the lugs 48. The member 44 at its upper end has a curved rib 56 projecting into a similarly curved slot in the arm 30 and at its lower end it has curved slots 58 and 60 (Fig. 5) into which project ribs 62 and 64 (Fig. 1) formed on a plate 66 secured to the lower end of the arm 30. By this means the member 44 is held on the arm 30 but permitted to turn about the common axis of curvature of the different ribs and slots. The tack drivers 36 also are so controlled as to permit them to turn with the member 44, the drivers being fast in a block 68 which is swiveled on a stud 70 on the lower end of a driver-operating bar 72 and is provided with a tongue 74 (Fig. 1) arranged to slide in a guideway between ribs 76 (Fig. 2) on the member 44. To maintain the member 44 and the parts that move therewith normally in a central position, while permitting them to turn as required, there is a spring plunger 78 in the arm 30 having a wedge-shaped lower end arranged to cooperate with a correspondingly shaped recess 80 in the member 44. The means for thus mounting and controlling the member 44 are generally similar to the disclosure of Letters Patent No. 1,029,387. 90

For adjusting each of the above-described upper-fastening mechanisms about its axis as the arm 30 which carries it is moved inwardly toward the shoe, and thus to position the different tack holders and drivers in proper relation to the shoe for driving the different tacks at the desired distances from the edge of the shoe bottom, each upper-fastening mechanism, in accordance with the present invention, is provided with means for engaging the side of the shoe in locations spaced a substantial distance apart lengthwise of the shoe. This means, as illustrated, consists of two metal blocks 82 and 84 arranged to engage the side of the shoe respectively at the front and at the rear of the locations where the group of tacks are driven, and also at the front and at the rear of the clamping pad 18, each block being pivotally mounted on a pin 86 on a plunger 88 which 100 110 115 120 125 130

supports it, so that it may turn about an axis extending heightwise of the shoe and thus adjust itself to the contour of the side of the shoe. A small spring-controlled plunger 90 within each plunger 88 is arranged to contact with a straight surface on the block 82 or 84 and thus normally to maintain it yieldingly in a centralized position. Each plunger 88 is mounted in a lateral extension of the holder 42 and is adjustable laterally of the shoe by means of a screw 92 which is threaded in the holder. A spring 94, connected at one end to the pin 86 and at its other end to a screw 96 in the holder 42 maintains the plunger 88 yieldingly against the end of the screw 92. It will be observed that the spring 94 connected to one of the plungers 88 is above the plunger, while the spring connected to the other plunger is arranged below it. Each screw 96 has on its end a stud 98 which projects into a slot in the plunger 88 to prevent the latter from turning. Each screw 92, moreover, is held yieldingly in adjusted position by a spring-pressed ball 100 (Fig. 4) which projects into one or the other of two slots 102 formed on opposite sides of the screw.

It will be seen that when each side arm 30 is swung inwardly toward the shoe, one or the other of the blocks 82, 84 engages the side of the shoe and causes the upper-fastening mechanism to turn about its axis until both the blocks are in contact with the shoe and thus determine the position of the mechanism with respect to movement about its axis and also limit its bodily movement widthwise of the shoe. Such direct control of the fastening mechanism by the shoe, independently of the yieldable side-clamping means, serves to insure that the different tacks will be driven in proper relation to the edge of the shoe bottom, whatever may be the shape and position of the shoe. It will also be evident that by adjustment of one or both of the screws 92 the relation between the tacks and the edge of the shoe bottom may be varied as desired.

Having described the invention, what I claim as new and desire to secure by Letters 50 Patent of the United States is:

1. In an upper-shaping machine, the combination with means for shaping the upper of a shoe over a last, of upper-fastening mechanism movable transversely of the edge 55 of the shoe bottom into upper-fastening position and constructed to drive a plurality of fastenings spaced apart along the edge of the shoe bottom, said upper-fastening mechanism being so mounted as to permit it to be turned about an axis extending heightwise 60 of the shoe to position the fastenings in proper relation to the edge of the shoe bottom, and means carried by said upper-fastening mechanism for engaging the shoe 65 positively to adjust the mechanism about

said axis in accordance with the shape and position of the shoe prior to the driving of the fastenings.

2. In an upper-shaping machine, the combination with means for shaping the upper of a shoe over a last, of upper-fastening mechanism movable transversely of the edge of the shoe bottom into upper-fastening position and constructed to drive a plurality of fastenings spaced apart along the edge of the shoe bottom, said upper-fastening mechanism being so mounted as to permit it to be turned about an axis extending heightwise of the shoe to position the fastenings in proper relation to the edge of the shoe bottom, and means carried by said upper-fastening mechanism for engaging the shoe in different locations spaced a substantial distance apart lengthwise of the edge of the shoe bottom to adjust the mechanism about 85 said axis in accordance with the shape and position of the shoe prior to the driving of the fastenings.

3. In an upper-shaping machine, the combination with means for shaping the upper of a shoe over a last, of upper-fastening mechanism movable transversely of the edge of the shoe bottom into upper-fastening position and constructed to drive a plurality of fastenings spaced apart along the edge of the shoe bottom, said upper-fastening mechanism being so mounted as to permit it to be turned about an axis extending heightwise of the shoe to position the fastenings in proper relation to the edge of the shoe bottom, and members carried by said upper-fastening mechanism for engaging the shoe positively in different locations spaced apart lengthwise of the edge of the shoe bottom to adjust the mechanism about 100 said axis in accordance with the shape and position of the shoe prior to the driving of the fastenings.

4. In a pulling-over machine, the combination with means for pulling the upper of a shoe over a last, of upper-fastening mechanisms movable laterally of the shoe at its opposite sides into upper-fastening positions and each constructed to drive a plurality of fastenings spaced apart lengthwise of the shoe, each of said upper-fastening mechanisms being so mounted as to permit it to be turned about an axis extending heightwise of the shoe to position the fastenings in proper relation to the edge of the shoe bottom, and means carried by each of said upper-fastening mechanisms for engaging the side of the shoe positively to adjust the mechanism about said axis in accordance with the shape and position of the shoe prior to the driving of the fastenings.

5. In a pulling-over machine, the combination with means for pulling the upper of a shoe over a last, of upper-fastening mechanisms movable laterally of the shoe at its opposite sides into upper-fastening position and

each constructed to drive a plurality of fastenings spaced apart lengthwise of the shoe, each of said upper-fastening mechanisms being so mounted as to permit it to be turned about an axis extending heightwise of the shoe to position the fastenings in proper relation to the edge of the shoe bottom, and means carried by each of said upper-fastening mechanisms for determining positively in accordance with the contour of the shoe the position of the mechanism with respect to movement about said axis prior to the driving of the fastenings.

6. In a pulling-over machine, the combination with means for pulling the upper of a shoe over a last, of upper-fastening mechanisms movable laterally of the shoe at its opposite sides into upper-fastening positions and each constructed to drive a plurality of fastenings spaced apart lengthwise of the shoe, each of said upper-fastening mechanisms being so mounted as to permit it to be turned about an axis extending heightwise of the shoe to position the fastenings in proper relation to the edge of the shoe bottom, and members carried by each of said upper-fastening mechanisms for determining by engagement with the side of the shoe in different locations spaced apart lengthwise of the shoe the position of the mechanism with respect to movement about said axis prior to the driving of the fastenings.

7. In a pulling-over machine, the combination with means for pulling the upper of a shoe over a last, of upper-fastening mechanisms movable laterally of the shoe at its opposite sides into upper-fastening positions and each constructed to drive a plurality of fastenings spaced apart lengthwise of the shoe, each of said upper-fastening mechanisms being so mounted as to permit it to be turned about an axis extending heightwise of the shoe to position the fastenings in proper relation to the edge of the shoe bottom, and members carried by each of said upper-fastening mechanisms for engaging the side of the shoe in different locations spaced apart lengthwise of the shoe to adjust the mechanism about said axis in accordance with the shape and position of the shoe prior to the driving of the fastenings, said members being adjustable to vary the relation of the fastenings to the edge of the shoe bottom.

8. In a pulling-over machine, the combination with means for pulling the upper of a shoe over a last, of upper-fastening mechanisms movable laterally of the shoe at its opposite sides into upper-fastening positions and each constructed to drive a plurality of fastenings spaced apart lengthwise of the shoe, each of said upper-fastening mechanisms being so mounted as to permit it to be turned about an axis extending heightwise of the shoe to position the fastenings in proper relation to the edge of the shoe bottom,

and members carried by each of said upper-fastening mechanisms for determining by engagement with the side of the shoe in different locations at the front and at the rear respectively of the group of fastenings the position of the mechanism with respect to movement about said axis prior to the driving of the fastenings.

9. In a pulling-over machine, the combination with means for pulling the upper of a shoe over a last, of upper-fastening mechanisms movable laterally of the shoe at its opposite sides into upper-fastening positions and each constructed to drive a plurality of fastenings spaced apart lengthwise of the shoe, each of said upper-fastening mechanisms being so mounted as to permit it to be turned about an axis extending heightwise of the shoe to position the fastenings in proper relation to the edge of the shoe bottom, and members carried by each of said upper-fastening mechanisms for engaging the side of the shoe positively in locations spaced a substantial distance apart lengthwise of the shoe to determine the position of the mechanism with respect to movement about said axis prior to the driving of the fastenings, each of said members being adjustable independently of the other in directions widthwise of the shoe to vary the relation of the fastenings to the edge of the shoe bottom.

10. In a pulling-over machine, the combination with means for pulling the upper of a shoe over a last, of means for clamping the upper at the opposite sides of the forepart of the last near the edge of the shoe bottom after the upper has been pulled, upper-fastening mechanisms movable laterally of the shoe at its opposite sides into upper-fastening positions and each constructed to drive a plurality of fastenings spaced apart lengthwise of the shoe, each of said upper-fastening mechanisms being so mounted as to permit it to be turned about an axis extending heightwise of the shoe to position the fastenings in proper relation to the edge of the shoe bottom, and means carried by each of said upper-fastening mechanisms for determining by engagement with the shoe independently of said clamping means the position of the mechanism with respect to movement about said axis prior to the driving of the fastenings.

11. In a pulling-over machine, the combination with means for pulling the upper of a shoe over a last, of means for clamping the upper at the opposite sides of the forepart of the last after the upper has been pulled, upper-fastening mechanisms movable laterally of the shoe at its opposite sides into upper-fastening positions and each constructed to drive a plurality of fastenings spaced apart lengthwise of the shoe, each of said upper-fastening mechanisms being so mounted as to permit it to be turned about

an axis extending heightwise of the shoe to position the fastenings in proper relation to the edge of the shoe bottom, and members carried by each of said upper-fastening mechanisms for engaging the side of the shoe respectively at the front and at the rear of said clamping means to adjust the mechanism about said axis in accordance with the shape and position of the shoe prior to the

5 driving of the fastenings.

In testimony whereof I have signed my name to this specification.

BERNHARDT JORGENSEN.
